F. B. DUES

SNAPPING ROLL

Filed April 17, 1922

Patented Nov. 4, 1924.

UNITED STATES PATENT OFFICE.

FRED B. DUES, OF MINSTER, OHIO.

SNAPPING ROLL.

Application filed April 17, 1922. Serial No. 553,473.

To all whom it may concern:

Be it known that I, FRED B. DUES, a citizen of the United States, residing at Minster, in the county of Auglaize and State of Ohio, have invented a new and useful Snapping Roll, of which the following is a specification.

This invention relates to snapping rolls for use in connection with corn harvesting machines, one of the objects of the invention being to provide rolls so constructed that when corn stalks break off and fall crosswise in front of the snapping rolls they will be straightened out and carried between the rolls without spreading the rolls apart and interfering with the snapping operation.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a view partly in section and partly in elevation of the mechanism constituting the present invention.

Figure 2 is an end elevation of one pair of snapping rolls.

Referring to the figures by characters of reference 1 designates snapping rolls arranged in pairs, all of the rolls being of the same construction although the rolls of each pair are oppositely disposed, one being designed to rotate in a clockwise direction and the other in a counter-clockwise direction. Each roll is mounted on a shaft 2 and the shaft of one roll of each pair is supported in stationary bearings 3 while the shaft of the other roll of each pair is mounted in slideable bearings 4. These slideable bearings are supported in guides 5 holding springs 6 which thrust against the bearings 4. The springs may be placed under different degrees of compression by screws 7. The shafts mounted in the stationary bearings 3 are provided

with gears 8 and these gears, in turn, mesh with gears 9 secured to short shafts 10. These shafts 10 are connected by universal joints 11 to those shafts mounted in the bearings 4. The outer ends of the shafts 10 are mounted in movable bearings 12 supported by a frame 13. Thus it will be seen that one roll of each pair is capable of moving away from and toward the other roll of said pair without interfering with the transmission of motion through the gears. A drive wheel 14 can be connected to one of the shafts 2.

Each of the snapping rolls is provided with longitudinal series of recesses or pockets 15, each pocket having its inner wall flat and tangent to an imaginary cylinder concentric with the roll while its other longitudinal wall is radially disposed as shown at 16 in Figure 2. Both walls of each groove are extended to the periphery of the cylinder or roll. Each roll is provided at diametrically opposed points with longitudinally extending flat faces 17 and formed within each of these flat faces is a longitudinally extending angular groove 18, these flat faces and grooves being extended throughout the length of the rolls.

When the apparatus is in operation the stalks will be received between the rolls and the radial walls 16 of the recesses will engage ears and snap them from the stalks. Should any of the stalks be presented crosswise to the rolls they will be directed into the longitudinal grooves 18 and be carried between the rolls without spreading them apart. It will be noted in Figure 2 that the grooves on the rolls of each pair are adapted to register during the rotation of the rolls.

What is claimed is:—

1. In a corn harvester, superposed pairs of snapping rolls each having longitudinal grooves extending from end to end and longitudinal series of pockets disposed in staggered relation between the grooves, each groove and each pocket having one wall disposed radially of the axis of rotation of the roll and having its other wall perpendicular to the radial wall.

2. In a corn harvester, a snapping roll having longitudinal grooves extending from

90

100

end to end thereof and longitudinal series of pockets extending from end to end between the grooves, the pockets of the series being staggered, the rear or following wall of each groove and pocket being disposed radially of the axis of rotation and the other wall of each groove and pocket being perpendicular to the radial wall thereof.

In testimony that I claim the foregoing as my own, I have hereto affixed my signature 10 in the presence of two witnesses.

FRED B. DUES.
